DESIGN FOR A LETTER TRAY

Earl S. Gavin, Ludlow, Ky., assignor to The Globe-Wernicke Company, Norwood, Ohio, a corporation of Ohio

Application December 10, 1941, Serial No. 104,560

Term of patent 14 years

To all whom it may concern:

Be it known that I, Earl S. Gavin, a citizen of the United States and a resident of Ludlow, in the county of Kenton and State of Kentucky,
have invented a new, original, and ornamental Design for a Letter Tray, of which the following is a specification, reference being had to the accompanying drawing, forming a part thereof.

In the drawing:

ing my design.

Fig. 2 is a side elevational view thereof;

Fig. 3 is a front elevational view thereof.

Fig. 4 is a rear elevational view thereof.

I claim:

The ornamental design for a letter tray, as shown.

EARL S. GAVIN.
